INDUCTOR BOBBIN

Albert Zack, Danvers, and Howard Stanton, Jr., Ipswich, Mass., assignors to Sylvania Electric Products, Inc., a corporation of Delaware

Filed Dec. 9, 1960, Ser. No. 74,960

8 Claims. (Cl. 336—208)

This invention relates in general to inductors and in particular to inductors having insulating bobbins which contain and insulate windings.

In conventional manufacturing of inductors, especially transformers, it is the practice to surround a portion of the core of the device with an insulating bobbin or sleeve. Such bobbins are commonly made of kraft paper, nylon, or other plastic, ceramic, asbestos, fiberglass or the like. These materials serve the function of insulation quite well, but they lack other desirable features such as physical strength, the ability to conduct heat and versatility, since each of the numerous transformer designs requires a particular size and configuration of bobbin. Insofar as physical strength is concerned, a particular problem arises in connection with direct-wound transformers. In these structures, the wire coils are wound on the core of the transformer itself rather than being wound elsewhere and assembled as a unit onto the core. In carrying out this process, a split bobbin must be fitted to the core, and the two sections must then be taped or otherwise fastened together. Such structure is, of course, inherently lacking in structural rigidity. Moreover, the thickness of the stock from which the bobbin is made becomes excessive adding to bulk and weight because loose tolerances and heavy materials must be used to compensate for the undesirable physical characteristics of conventional bobbins.

A most important fault in inductors constructed in accordance with present concepts stems from the inability of the bobbin to conduct and transfer heat generated by the coil and the core of the unit. This fault compels the use of very heavy windings in inductors designed to handle large currents. Indirectly, it also results in an unwieldy and physically unsound structure in which the coil or coils are largely unsupported as they bulk out from the core.

It is therefore an object of the present invention to improve inductors, particularly transformers.

It is another object of the present invention to provide transformers of smaller size but of ratings equal to those of transformers presently being made.

It is a further object of the present invention to reduce the operating temperature of inductors.

It is a still further object of the present invention to provide a more stable and rugged design for transformers.

In general, the present invention is organized about an inductor having a metallic bobbin stamped in a desired pattern from metal and coated on certain of its surfaces with resin, plastic or varnish. The bobbin may be in two pieces joined by laminations of the inductor core, or it may be a single self-supported member.

In either case, uncoated surfaces of the bobbin are placed in intimate contact with laminations which make up the core of the device. In some instances, it is desirable to actually weld the bobbin to adjacent laminations.

The bobbin includes in addition to the portion which is in intimate contact with the laminations a set of flanges extending outwardly from that portion. These flanges serve to contain the coil which is subsequently wound upon the structure to form the inductor. On those areas of the bobbin which are in contact with the coil, insulation is obtained preferably by use of resin coating, although other plastics or varnishes are adequate in many

2

cases. Space is provided on the flanges for the addition of cooling fins or other radiating surfaces. For a better understanding of the present invention together with further objects, advantages and features, reference should be made to the following specification which should be read in conjunction with the drawings, in which:

FIG. 1 is an exploded view, partially cut away, of a transformer having a bobbin which contains two sets of laminations;

FIG. 2 is a side elevation of one of the bobbin members of FIG. 1;

FIG. 3 is an end elevation of the same bobbin member;

FIG. 4 is a side elevation of a self-supported bobbin; and

FIG. 5 is an end elevation of the same self-supported bobbin.

The inductor illustrated in FIG. 1 is a transformer utilizing formed core laminations, and the invention will be explained in connection with such an embodiment. However, the invention may also be applied to inductors of any kind, including those in which stacked E-I laminations are used and those which utilize C-cores. In FIG. 1, however, there is shown a pair of similar bobbin members 12, preferably made of cold rolled steel stampings.

The ends of the two similar bobbin members extend outwardly and are bent to form flanges 16. Central openings are formed in the bobbin members to accommodate similar sets of laminations 18 and 20. The ends of the innermost lamination of the group 18 are preferably welded to the adjacent surfaces of the bobbin members. Similarly, the ends of the innermost lamination of the group 20 are welded to corresponding surfaces of the bobbin members adjacent the central opening. In this fashion, thermal contact surfaces, of which the surface 21 is typical, are formed between the laminated core and the bobbin members.

A coil or coils 26 are wound upon the outer periphery of the structure 25 formed by the enclosed portions of the lamination groups 18 and 20. In order to provide suitable electrical insulation between the enclosed portion 25 and the innermost windings of the coil 26, insulation is provided on the exterior surface of the enclosed portion 25. One of the most suitable substances from which the insulation may be made is epoxy resin, with which the outer surface of the enclosed portion 25 is fluidized. The fluidizing operation is also carried out to the extent that the inner surfaces of the flanges 16 adjacent the enclosed portion 25 and which come in contact with the coil 26 are also fluidized with resin. Materials such as Teflon, nylon or vinyl may also be used for the necessary insulation. In fact, simple varnishes are adequate in some situations where voltages are not extreme.

The ends of the lamination groups 18 and 20 are composed of alternate long and short extensions to permit the interleaving therewith of similarly arranged lamination groups 27 and 28 to complete the inductor structure.

In FIGS. 2 and 3, one of the bobbin members is illustrated as it appears before it is assembled with the lamination groups. It will be noted that a slot is provided through the flanges at one end of the bobbin side members. This slot serves the dual purpose of preventing the flange from acting as a shorted turn and further permits the assembly of the laminations into the bobbin side members without the need for distorting the side members during the assembly process. The slot is, of course, unnecessary in D.C. units.

In FIGS. 4 and 5, a modification of the basic structure is illustrated. In this instance, a self-supported bobbin is provided in which the laminations themselves are not utilized as a component of the bobbin proper. Such a structure is useful where the winding is made external

to the assembly, and particularly where laminated cores of the E-I type are used.

In FIG. 4, there may be seen a stamping 42, through which a generally rectangular opening 43 is formed. A slot 44, which serves the same purpose as the slot in the bobbin member illustrated in FIGS. 2 and 3, extends from the central opening 43 through the entire upper portion of the bobbin. If laminations of the formed core type are used, two sets of such laminations are passed through the opening 43, much like the manner in which the laminations are contained between bobbin members of the structure of FIG. 1. If, on the other hand, laminations of the E-I type are utilized, the central leg of those laminations would be passed through the opening 43. In either case, the coil would preferably be wound around the reduced central portion 45, best seen in FIG. 5. Here again, an epoxy resin is fluidized upon the reduced portion 45 and also upon the adjacent flanges such as 46. In other words, all surfaces of the bobbin which might otherwise be in contact with the coil are coated with an insulating material, preferably epoxy resin which is fluidized upon those surfaces.

The self-supported bobbin illustrated retains the features of the embodiment previously described. For example, it includes flanges 47 which serve to contain the coil as well as to provide heat conduction and radiation to permit cooler operation of the inductor. Of course, radiation fins or other suitable structures may be mounted upon the flanges to further enhance the removal of heat. Inasmuch as the laminations are in direct thermal contact with the interior of the reduced portion 45, heat conduction and removal are effectively accomplished. Moreover, despite the presence of the insulation between the coil and certain of the surfaces of the structure, heat developed in the coil is removed much more efficiently than would be the case where bobbins of poor heat conducting characteristics are utilized.

Although what has been described constitutes preferred embodiments of the invention, numerous alternatives will suggest themselves immediately to those skilled in the art upon a reading of the specification. These alternatives might include the use of an integral part of the magnetic structure as the bobbin material as, for example, a structure where the first lamination of the core also serves as the bobbin flange. Other alternatives such as simple substitution of other metals for the bobbin material, changes of insulating material, or minor variations in configuration of the device, are believed to be within the purview of the invention. The invention should, therefore, be limited only by the spirit and scope of the appended claims.

What is claimed is:

1. An inductor comprising a core composed of a plurality of laminations formed into a closed configuration and having a pair of openings therethrough, a portion of said laminations forming a central leg across said opening, at least one metallic bobbin surrounding said central leg and in intimate contact therewith, said bobbin including flanges extending outwardly and perpendicularly from the portion thereof surrounding said central leg, said central leg having end portions extending in a direction parallel to said flanges, insulating material disposed upon the outer surfaces of said central leg, said portion of said bobbin surrounding said central leg, and upon the inner surfaces of said flanges, and at least one coil wound about said central leg and said portion of said bobbin surrounding said central leg and contained by and substantially within said flanges.

2. An inductor comprising a core composed of metal laminations formed in a closed configuration having at least one opening therethrough, at least a coil linked to said core through said opening, a metallic bobbin surrounding a portion of said laminations and welded to the flat portions thereof in immediate contact with said bob-

bin, and insulating material on certain of the surfaces of said bobbin, said coil being disposed in close contact with said insulating material.

3. An inductor comprising a core composed of two sets of laminations, each of said sets being formed with an opening therethrough, said sets being disposed adjacent one another, a coil wrapped about said laminations and passing through said openings, a pair of metallic bobbin end members welded to portions of said laminations to form a bobbin therewith and holding said sets in position adjacent one another and insulating material disposed upon surfaces of said laminations and of said bobbin end members to form a layer of said insulating material between said coil and said laminations and bobbin end members.

4. An inductor comprising two sets of laminations, each said set of laminations being formed from two halves of a closed loop of nested laminations, a nested half of one set being disposed adjacent a nested half of the other set, a pair of metallic bobbin end members each having an opening therethrough, said adjacent nested halves passing through and being contained within the openings in said bobbin end members, a layer of insulating material disposed upon certain surfaces of said adjacent nested halves and of said metallic bobbin end members, at least one coil wrapped about said layer of insulating material upon said nested halves and in contact with said layer of insulating material upon said metallic bobbin end members, said metallic bobbin end members being welded to the innermost laminations of said nested halves, each other half of said set of laminations being joined to one of said nested halves to complete said closed loops of laminations about said coil, and a layer of insulating material between said coil and each said other half of each of said sets of laminations.

5. An inductor as defined in claim 4 wherein each said nested half of a set of laminations includes alternately long and short ends and each said other half of each set of laminations also includes alternately short and long ends, said closed loops being formed by interleaving ends of said halves.

6. An inductor comprising a core of two U-shaped stacks of magnetic material, said U-shaped stacks being placed against each other back-to-back, with the open ends of the U-shaped stacks facing away from each other, bobbin end members of metal extending outward from the middle portion of said core in the general direction of the outwardly extending legs of the U-shaped members and welded to some of the laminations of said core to form with the middle portions of the U-shaped members a bobbin on which a coil can be wound, and a coil wound on said bobbin.

7. The combination of claim 6, in which each bobbin end members has a slot on one side, the bobbin end members being placed on the core so that the slots extended outward from the plane of the U-shaped sides of the U-shaped members.

8. In an inductor as defined in claim 6, integral flanges extending outwardly from said bobbin ends, said coil being insulated from adjacent surfaces of said flanges.
